**TRIPLE SECTION MAST WITH HIGH
FREE LIFT**

George P. Marco, Homewood, Ill., assignor to Allis-Chalmers Manufacturing Company, Milwaukee, Wis.

Filed Apr. 13, 1967, Ser. No. 630,756

5 Claims. (Cl. 187—9)

ABSTRACT OF THE DISCLOSURE

The drawings illustrate a high free lift triple section mast for a lift truck having low collapsed height and relatively high extended height. Two of the three components of the lift jack are connected to two of the three sections of the mast and the third component of the lift jack carries a pulley engaging a flexible lift element secured at one of its ends to the carriage and at its other end to the stationary mast section. The flexible lift element is also reeved about pulleys at opposite ends of mast section on which the load carriage is mounted.

This invention relates to a triple section mast wherein the load carriage may be raised to the collapsed height of the mast before the mast height is increased. In other words this invention relates to a high free lift, triple section mast.

A high free lift mast is particularly useful in loading and unloading box cars or semitrailer trucks. In such operations it is also desirable that the collapsed height of the mast be fairly low so that the lift truck may be moved through low doorways, such as those encountered in box cars, trucks and some warehouses. While a low collapsed height of the mast is desired, the warehouse to or from which the cargo is being moved may have a sufficiently high ceiling to permit stacking of stored material to a fairly high height. Thus it is often desired that the mast with low collapsed height also have a relatively great extended height. It is a primary objective of the present invention to provide a mast which fulfills the hereinbefore outlined requirements in an entirely satisfactory manner.

It is a further object of this invention to provide a mast of the hereinbefore character which is economical to manufacture and is entirely satisfactory in operation.

It is a further object of this invention to provide a high free lift mast assembly with at least three sections wherein the lift jack and chain and sprocket arrangement insure the proper sequence of movement of the mast sections without requiring use of latches.

These and other objects and advantages of this invention will be apparent to those familiar with the art when the following description is read in conjunction with the drawings in which:

FIG. 1 is a vertical section view of a triple section mast incorporating the present invention;

FIG. 2 is a view of the mast shown in FIG. 1 with the carriage raised to the top of the mast to illustrate the full free lift available;

FIG. 3 is a view of the mast shown in FIGS. 1 and 2 with the mast extended to an intermediate position;

FIG. 4 is another view of the mast shown in FIGS. 1, 2 and 3, but extended to its full height;

FIG. 5 is an enlarged top view of the mast taken along the line V—V in FIG. 1; and

FIG. 6 is an enlarged section view taken along the line VI—VI in FIG. 3.

As shown in the drawings, the mast assembly includes a stationary outer or primary section 11 pivotally mounted on a lift truck chassis 8 by pins 9, 9'. The primary mast section has a pair of brackets 10, 10' adapted for

2

connection to tilt jacks, the brackets being welded to upright guide or channel members 12, 13 which are tied together by cross braces 14, 15 and a bottom plate 16. A pair of rollers 17, 18 are rotatably secured to the channel members 12, 13 and extend through cutout portions 19, 21 to engage upright guide members or I-beams 22, 23 forming part of a second or intermediate mast section 24. The I-beams 22, 23 are tied together by cross braces 26, 27 and carry a pair of rollers 28, 29 which extend through notches 33, 34 and abut I-beams 31, 32 of an inner or third mast section 30. The inner mast section 30 is reinforced by a cross member 36 secured to the top of guides 31, 32 and by a cross member 37 secured to the lower rear of the I-beams or guide members 31, 32. A lift fork carriage 41 with forks 40 is mounted for vertical reciprocal movement in the guide members 31, 32 by rollers 42, 43. A lift mechanism, 7 including a hydraulic jack 46 and flexible lift elements in the form of a pair of continuous sprocket chains 47, 47', is employed for operating the mast. The chains 47, 47' are anchored at one end to the carriage, as at point 48, and to the bottom of the outer mast section 11 as at point 49. Between the carriage and primary mast section the chains 47, 47' are reeved over a pair of pulleys in the form of sprockets 51, 51' thence over a pair of pulleys in the form of sprockets 52, 52' pivotally mounted to the bottom of the inner mast section 30, thence over a pair of pulleys in the form of sprockets 53, 53' mounted on the upper end of component 54 of jack 46. The jack 46 is a commercially available high free lift cylinder assembly. As shown in FIG. 1, the extensible cylinder component 54 of jack 46 is in its retracted position and the carriage 41 is in its lowermost position. When the jack 46 is initially supplied pressure fluid from pump 71 through control valve 72 and conduit 73, the cylinder component 54 will telescopically displace itself upwardly relative to the outer cylindrical component 56. The component 56 includes an integrally formed inner cylindrical portion 57 which extends the entire collapsed height of jack 46. The cylinder component 54 is in the nature of a sleeve which mounts a crosshead 58 carrying sprockets 53, 53'. The upper end of cylinder part 57 is secured to a bracket 59 at the upper end of the intermediate mast section 24.

As will be noted in FIG. 2, the carriage 41 has been raised to the top of the mast in its collapsed condition. Thus the mast provides full free lift. Free lift refers to the distance which the carriage can be raised from the floor before the mast is extended in height. Thus it will be apparent that normal cargo carried by the forks 40 on the carriage may be raised to the uppermost position required within a box car or truck without danger of the mast being pushed through the roof. Upon a predetermined quantity of pressure fluid being supplied to jack 46, the carriage will move to its one hundred percent free position illustrated in FIG. 2 and when additional pressure fluid is supplied to the jack 46, the cylinder component 56 will be moved upwardly relative to stationary component or inner cylinder 61 which has its bottom end secured to the cross plate 16 at the bottom of the outer mast section 11. This will cause the intermediate mast section 24 to move upwardly relative to the outer mast section 11 and will simultaneously cause the inner mast section and carriage 41 to move upwardly relative to intermediate mast section 24.

As shown in FIG. 3 the mast has been extended to an intermediate position and as shown in FIG. 4 the jack 46 has been completely extended which has caused the mast to be extended to its highest position.

From the foregoing description it will be apparent that I have provided an extremely useful and novel triple section high free lift mast assembly affording low collapsed

height for low doorways of box cars and trucks and relatively high extended height for stacking cargo in high ceiling warehouses.

The embodiments of the invention for which an exclusive property or privilege is claimed are defined as follows:

1. In a multiple section mast assembly for a lift truck, an upright primary mast section for stationary mounting on a lift truck, a second mast section mounted for relative vertical reciprocal movement on said primary mast section, a third mast section mounted for relative vertical reciprocal movement on said second mast section, a carriage mounted for relative vertical reciprocal movement on said third mast section, a hydraulic jack mounted upright on said mast and having first, second and third relatively reciprocable components, the first component being secured to the bottom end of said primary mast section and the second component being secured to said second mast section, a first pulley on the upper end of said third mast section, a second pulley on the bottom end of said third mast section, a third pulley on said third component of said jack, and a flexible lift element having opposite ends secured to said carriage and primary mast section, respectively, and reeved sequentially from said carriage to said primary mast section over said first, second and third pulleys, initial predetermined supply of pressure fluid to said

jack causing said third component to move said carriage to the upper end of said third mast section without moving said mast sections upwardly and further supply of pressure fluid to said jack extending the latter causing said carriage and third mast section to move upwardly relative to said second mast section and simultaneously causing the latter to move upwardly relative to said primary mast section.

2. The structure set forth in claim 1 wherein said third component of said jack moves upwardly upon said jack being initially supplied with pressure fluid and wherein said third pulley is on the upper end of said third component of said jack.

3. The structure set forth in claim 1 wherein the upper end of said second jack component is secured to the upper end of said second mast section.

4. The structure set forth in claim 3 wherein said third pulley is on the upper end of said third component of said jack.

5. The structure set forth in claim 4 wherein said flexible element is secured at one of its ends to the lower end of said primary mast section.
